5 Claims. (Cl. 28—46)

This invention relates to an improved apparatus for separating magnetizable drop wires which are situated in a number of groups on guide rods and are designed to indicate breakage in threads of a warp in a loom. On each of the threads of the warp a drop wire is suspended, the thread being carried through a hole in the drop wire. In case a thread breaks the drop wire will fall down into a position showing that the thread is broken. In this new position the drop wire may possibly actuate members stopping the loom. Since the warp must have room for the drop wires the latter are arranged in several laterally positioned groups transversely of the warp.

There is already an apparatus which has magnets which are separately moved forwards towards a group of drop wires and grip a drop wire at the same time as a wedge is moved in from the side between the foremost drop wire and the remaining drop wires, which are thus separated, whereafter the foremost drop wire is retained while a warp thread is passed through its hole. From a mechanical point of view such an apparatus is rather complicated and consequently expensive to make. Sometimes the apparatus is mounted in such a way that at the same time as the thread is passed through the hole in the drop wire, the thread is carried through one of the various implements of the loom, for instance the heddles. The insertion of the threads through the heddles and the drop wires is generally undertaken by two persons of which one separates a thread from the warp while the other passes a hook mounted at the end of a rod through the heddle and the drop wire, catches the thread with the hook and pulls the thread through the drop wire and the heddle. On account of the distance between the drop wire and the heddle the rod with the hook must be comparatively long, up to about 50 cm. Such a long rod with a hook is difficult to handle, and the operator will soon get tired from the necessary great movements of his arms. Consequently it will generally be more advantageous and time-saving to draw the thread through the drop wire and the heddle in two operations.

The object of the present invention is to overcome these difficulties and disadvantages and to provide an apparatus for separating magnetizable drop wires which are to be placed on the warp threads to indicate breakage in the threads.

The invention contemplates in an apparatus for separating magnetizable drop wires which are situated in a number of groups on guide rods and are designed to indicate breakage in warp threads, the combination of a frame, a carriage movable on the frame, and means to drive the carriage, holding magnets in a number corresponding to the number of groups of drop wires and placed stationary on the carriage with the magnets aligned with the guide rods and facing the groups of drop wires thereon, a lever displaceably mounted on the carriage, on which lever there is mounted gripping magnets in a number corresponding to the number of groups of drop wires, which gripping magnets, when the lever is moved forwards, are displaced towards the drop wires and each grips the foremost drop

2

wire of each of the groups of drop wires and by a displacement backwards of the lever places the drop wires on the holding magnets which hold the drop wires while the warp threads are being passed through the drop wires, means for the displacement forwards and backwards of the lever and means for the displacement of the gripping magnets vertically simultaneously with the displacement forwards and backwards.

Further and important objects will become evident from a reading of the following detailed description in the light of the attached drawings, in which

Fig. 1 shows the apparatus, viewed in vertical section at the line I—I in Fig. 2,

Fig. 2 is a horizontal section at the line II—II in Fig. 1,

Fig. 3 is a horizontal section at the line III—III in Fig. 1,

Fig. 4 is a front view,

Fig. 5 is a detail plan view partly in section showing a modified form of mounting of the holding magnets, and

Fig. 6 is a detail side view of a part of Fig. 5.

The apparatus has a carriage frame 1, in which are mounted carriage wheel shafts 2 and 3 with supporting and driving wheels 4 by means of which the carriage can move on the rails 5 mounted on a frame not shown in the drawing. The drop wires 6 have holes or slots 7 by means of which the drop wires are suspended on a balance or guide rod 8. Moreover, each of the drop wires has a hole 9 through which a warp thread can be passed. Furthermore the apparatus is provided with holding magnets 10 arranged on arms 11 mounted on the carriage frame 1. The holding magnets may be mounted in a row with their holding faces in a plane at right angles to the moving direction of the carriage, i.e. at right angles to the rails 5, as shown in the drawing Fig. 2, but the magnets may equally well be arranged in an oblique row in such a way that their holding faces will be in a plane at an angle of less than 90° to the direction of movement of the carriage, as shown in the drawing Fig. 5. The holding surfaces of the magnets are then correspondingly oblique. In both instances the magnets may be mounted on arms 11 of different lengths so that the magnets may be displaced relative to each other in the direction in which they move. Generally four to six groups or rows of drop wires are used and a corresponding number of magnets. The drawing shows six groups of drop wires and six magnets corresponding thereto. Moreover, the apparatus has a number of gripping magnets 12 corresponding to the number of groups of drop wires and mounted on supports 13 which are arranged displaceably in guiding members 14 arranged on a holder 15 which is carried by a lever 16 having an elevated rear portion which by an obliquely positioned or offset portion 16a is connected to a lower positioned portion 16b. Between the magnets 12 and the guiding members 14 there are around the supports 13, helical springs 17 giving the supports 13 with the magnets 12 a certain movability in the axial direction of the supports, which movement is limited in the downward direction by pins 18 which are passed through the supports above the guiding members 14. The rear part of the lever has its rear end connected by a pivot 19 to an arm 20 which is rigidly mounted on a toothed rack 21. The latter can be moved forwards and backwards in its longitudinal direction, and during such movement, is guided at its under side by means of a bracket 22 arranged on the carriage 1, and guided at its upper side by means of a bracket 23 which is likewise mounted on the carriage 1 and grips round a rail 24 on the toothed rack 21. The lever 16, 16a, 16b is during its reciprocating movement guided by means of a pin 25 mounted on the carriage frame 1 and passing through a slot 26 in the lever and having outside the lever a disc or head 27. Moreover, the forward portion 16b of the lever is guided between a couple of arms 28 mounted

on the carriage frame 1 and between which there is on a shaft 29 carrying a rotatable roll 30 supporting the lever. The obliquely positioned portion 16a of the lever will cause the gripping magnets 12 mounted on the lever to be lowered during their movement against the drop wires 6 to the position shown with dotted lines in Fig. 1 and to be lifted during their movement against the holding magnets 10. The reciprocating movement of the toothed rack 21 is brought about in the manner of construction of the apparatus shown in the drawing by means of a mechanism having a cogged wheel 32 engaging with the toothed rack 21 and arranged on a shaft 33 mounted in the carriage frame. On the said shaft 33 there is furthermore arranged a cogged wheel 34 engaging with a cogged wheel 35 mounted on a shaft 36 journaled in the carriage frame 1. On the shaft 36 there is arranged at the upper side of the carriage frame, a cogged wheel 37 engaging with a toothed rack 38 which can be moved forwards and backwards in its longitudinal direction by means of a crank or eccentric mechanism 39 driven in the conventional manner by an electric motor, not shown in the drawing. The toothed rack 38 is guided in its movement by means of a guiding member 40 mounted on the carriage frame 1. The apparatus is moved forward against the drop wires 6 by means of a mechanism having a warping drum round which is wound a tightened cord 42 the two ends of which are fastened to the frame carrying the rails 5. The warping drum is in fixed connection with a pawl wheel 43, and both parts are arranged to rotate freely on the driving wheel shaft 3. Moreover, the mechanism has a pawl 44 arranged in a holder 45 oscillatorily mounted on the shaft 3. The pawl 44 is kept in engagement with the pawl wheel 43 by means of a helically wound spring 46 extended between the pawl and the carriage frame. The holder 45 is swung to and fro by means of a pulling rod 47 in linked connection with the same. The other end of the pulling rod 47 is in linked connection with an arm 48 which can swing on a pin 49 on the carriage frame 1. Moreover, the pulling rod 47 has an arm 50 which, by means of a helically wound spring 66 extended between the holder 45 and the carriage frame 1, is kept against a pin 51 on an arm 52 which is fixedly mounted on the alternately rotated shaft 36. The magnitude of the swinging movement of the holder 45 and consequently the turning of the warping drum 41 can be limited and adjusted by means of a screw 53 arranged in the carriage frame, which screw 53 is adjusted in relation to the holder 45. In order to prevent an unintended turning back of the warping drum 41 there is arranged in a holder 54 on the carriage frame 1, a counter pawl 55 kept in engagement with the pawl wheel 43 by means of a helically wound spring 56 extended between the pawl and the carriage frame. The apparatus is in a manner known per se equipped with electric starting and stopping members arranged in such a way that the apparatus is started by a manual pressure on a button closing the electric current, and the apparatus is automatically stopped when the current is interrupted after it has performed a working period, i.e., whenever a set of drop wires has been separated.

When the drop wires 6 have been moved to the holding magnets 10 as shown in dotted lines in Fig. 1, and the warp threads have been passed through the holes in the drop wires, the drop wires are manually pushed a little backwards relative to the magnets and still suspended on the guiding rods 8.

What I claim by my invention and desire to secure by Letters Patent in the United States is:

1. In an apparatus for separating magnetizable drop wires which are situated in a number of groups on guide rods and are designed to indicate breakage in warp threads, the combination of a frame, a carriage movable on the frame, and means to drive the carriage, holding magnets in a number corresponding to the number of groups of drop wires and placed stationary on the car-

riage, each of said magnets alined with a respective guide rod and facing the group of drop wires thereon, a lever displaceably mounted on the carriage, on which lever there are mounted gripping magnets in a number corresponding to the number of groups of drop wires, which gripping magnets, when the lever is moved forwards, are displaced towards the drop wires and each grips the foremost drop wire of the respective groups of drop wires, and by a displacement backwards of the lever place the drop wires on the holding magnets which hold the drop wires while the warp threads are being passed through the drop wires, means for the displacement forwards and backwards of the lever and means for the displacement of the gripping magnets vertically simultaneously with the displacement forwards and backwards.

2. In an apparatus for separating magnetizable drop wires which are situated in a number of groups on guide rods and are designed to indicate breakage in warp threads, the combination of a frame, a carriage movable on the frame, and means to drive the carriage, holding magnets in a number corresponding to the number of groups of drop wires and placed stationary on the carriage, each of said magnets alined with a respective rod and facing the group of drop wires thereon, said holding magnets being placed in a row in such a manner that they will be disposed in a plane at an angle less than 90° to the direction of movement of the carriage, a lever displaceably mounted on the carriage, on which lever there is mounted gripping magnets in a number corresponding to the number of groups of drop wires, which gripping magnets, when the lever is moved forwards, are displaced towards the drop wires and each grips the foremost drop wire of the respective groups of drop wires, and by a displacement backwards of the lever place the drop wires on the holding magnets which hold the drop wires while the warp threads are being passed through the drop wires, means for the displacement forwards and backwards of the lever and means for the displacement of the gripping magnets vertically simultaneously with the displacement forwards and backwards.

3. In an apparatus as claimed in claim 2 having holding magnets the holding surfaces of which are disposed in a plane at an angle less than 90° to the direction of movement of the carriage.

4. In an apparatus for separating magnetizable drop wires which are situated in a number of groups on guide rods and are designed to indicate breakage in warp threads, the combination of a frame, a carriage movable on the frame, and means to drive the carriage, holding magnets in a number corresponding to the number of groups of drop wires and placed stationary on the carriage, each of the magnets alined with a respective guide rod and facing the group of drop wires thereon, a lever displaceably mounted on the carriage, on which lever there are mounted gripping magnets in a number corresponding to the number of groups of drop wires, which gripping magnets, when the lever is moved forwards, are displaced towards the drop wires and each grips the foremost drop wire of each of the groups of drop wires and by a displacement backwards of the lever place the drop wires on the holding magnets which hold the drop wires while the warp threads are being passed through the drop wires, said combination further including means for the displacement forwards and backwards of the lever, said lever having an elevated portion which by an obliquely positioned portion is connected to a lower positioned portion, the said elevated portion has at its free rear end a linked connection with driving means for the displacement forwards and backwards of the lever, the said lower positioned portion carries at its free front end the said gripping magnets, the lever being guided in its vertical movement by means of a pin stationarily mounted on the carriage, which pin extends through a slot in the elevated portion of the lever and said lever is sup-

ported by a roll mounted on a second stationary pin on the carriage and said pin is placed in such a manner that when the obliquely positioned portion of the lever, during the forward movement of the lever, passes the said roll, the gripping magnets will be lowered towards the drop wires to be gripped, and that the gripping magnets during the backward movement of the lever will be lifted to their starting position when the obliquely positioned portion of the lever passes over the said roll, and means for the vertical displacement of the gripping magnets in relation to the lever on which they are mounted.

5. In an apparatus as claimed in claim 4, in which the vertically displaceable gripping magnets are mounted on

supports which are arranged displaceable against springs in the vertical direction in guiding members mounted at the front end of the said lever.
